(57) **CLAIM**

We claim the ornamental design for an aircraft, as shown and described.

DESCRIPTION

FIG. 1 is a top, right front perspective view of an aircraft showing our new design;

FIG. 2 is a right side elevational view, the left side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

1 Claim, 6 Drawing Sheets
